Geo. E. Clark
ATTORNEY

UNITED STATES PATENT OFFICE.

JAMES A. H. BELL, OF TOLEDO, OHIO.

LIGHT-CLEANING APPARATUS.

Application filed March 7, 1921. Serial No. 450,441.

To all whom it may concern:

Be it known that I, JAMES A. H. BELL, a citizen of the United States of America, residing at Toledo, Lucas County, Ohio, have 5 invented new and useful Light-Cleaning Apparatus, of which the following is a specification.

This invention relates to features of maintaining illumination.

10 This invention has utility when incorporated in cleaning mechanism for light transmitting and light reflecting surfaces, more especially as involved in incandescent lamp bulbs and dispersing reflectors therefor.

15 Referring to the drawings:

Fig. 1 is a side elevation, with parts broken away, of an illuminating device having the wiper of this invention incorporated therewith, in running position;

20 Fig. 2 is a detail of the embodiment of the device of this invention disclosed in Fig. 1, with the parts in inactive or idle position, the illuminating device being shown in dotted lines; and

25 Fig. 3 is a bottom plan view of the device with the wiper therein; Fig. 4 is a time controlled wiper installation; and

Fig. 5 is a thermostatic controlled wiper installation.

30 A socket 1 is shown as having mounted therein an incandescent electric light bulb 2 having a circular light transmitting surface 3 about light emitting filament 4. The socket 1 also carries a reflector 5 having an

35 inner circular surface 6 for concentrating, dispersing or directing rays of light from the filament 4 passing through the lamp bulb surface 3. Electric current supply lines 7, 8, extend to the socket 1 in supplying electric

40 energy to the bulb in completing the illuminating device.

Electric current supply lines 9, 10, in passing switch 11, may have current flow manually controlled in the lines 12, 13, to motor

45 14 mounted adjacent the socket 1. This motor 14, has shaft 15 carrying pulley 16 about which extends belt 17 driving rotary member or pulley 18 of a tubular bearing member embracing the bulb 2 and disposed

50 concentrically of the bulb 2 and reflector 5, as to their respective circular surfaces 3, 6. Fixed bearing 19 between the reflector 5 and the socket 1 carries the rotary member 18.

Depending from the member 18 is a 55 bracket 20 having pivot pin 21 for an arm

22 carrying a brush or wiper element proper 23. This wiper member 22, 23, may have its wiping or cleaning element 23 configured to approximate a section of the curved surface of the reflector 5. Near the outer terminus of the member 22 is a weight 24 as a loading means tending to make more quickly responsive the swinging clear of the surface, as well as more positive, the holding into surface engaging position.

This reflector wiper member 22 has a depending ear 25 from which extends link 26 to pivotal connection 27 with link 28 carried by pivot pin 29 mounted in depending bracket 30, similar to the bracket 20, and 60 carried by the rotary member 18 approximately diametrically opposite to the bearing 20. Pivot bearing 31 connects the link 28 with bulb surface wiper member 32 having thereon wiper element proper 33 curved 75 to conform to a section of the circular outer surface of the bulb 2. To assist in distributing more uniformly the load on the fixed bearing 19, there extends from the bracket 30 a weight 34.

At rest, the reflector wiper member 22 tends to fall away from the reflector surface 6, in a swinging movement on the pivot pin 21. This shifting may be assisted by weight or loading means 24. Through links 26, 28, 80 the bulb surface wiper member 32 is simultaneously shifted outward or away from bulb surface. This means that the apparatus at rest is not in position as to either wiper to pack any grime or dust against the 85 light bulb or reflector surface.

In operation, at such intervals as may be desirable, the switch 11 may be thrown for quick short duration cleaning of a lamp or group of lamps. The driving motor 14, 95 herein shown as an independent element mounted on the reflector support, instead of incorporated therein for direct drive, in its rotation at high speed of the rotary member 18, has the major or longer radius reflector 100 wiper member 22 controlling not only to swing itself in cleaning position against the surface 6 of the reflector, but through the links 26, 28, pull the member 32 against the bulb surface 3. The fumes, dirt, or grime 105 arising in the factory, foundry, or other place of installation may govern the character of wiping elements, as to coarse character approximating a brush, to the fineness of felt. When the switch 11 is opened, 110

the members 22, 32, fall away from surface contacting positions. The wiper of this disclosure is accordingly always in position for remote control in maintaining illumination efficiency even over difficultly accessible work, a material feature in reducing hazards to workmen.

This wiper construction is conveniently installed for automatic operation. For instance, as shown in Fig. 4, a remote control circuit may have a battery 34 connected by line 35 to a clock 36 from which may extend line 37 to coil 38. The clock 36 may be provided with a switch connection controlling the energizing of the coil 38 for a brief interval, as one minute, during each hour, or for a brief interval once in every twelve hours, or other intervals.

When this coil 38 is energized, it serves to close switch 39 and thereby permits flow of current from the line 7 by way of the line 40 to the control line 41 having leads 12 therefrom to the motors 14 thereby causing the motors 14 to rotate the wipers 22, 33, in cleaning the bulbs 3 and the reflectors or shades 5.

There may be a unit dust proof housing 42 for the combined socket and motor of the installation.

As shown in Fig. 5, the throwing in of the switch 43 to light the lamp 2 may operate automatically for a brief period to drive the motor 14 for operating the wiper. To this end the supply line 8 has heating coil 44 about expansion member 45. This line leads from the coil 44 by way of coil 46 to solenoid 47 and thence to the lamp 2 with the other side by way of the line 7 completing the circuit.

As the current through the coil 46 lights the lamp 2, solenoid 47 is operated to close switch 48 thereby from the line 7 by way of line 49 connecting to one side of wiper driving motor 14. Line 50 from the other side of this motor going by way of switch 51 and the bar 45 to the line 8 completes this circuit. However, as the lamp 2 is continued lighted, the current in the coil 44 tends to bow the bar 45 by heat expansion and open the switch 51, thereby automatically stopping the motor 14 after a brief cleaning or wiping operation. Accordingly, in this disclosure of Fig. 5, at each interval of turning on of the light there occurs an automatic cleaning.

What is claimed and it is desired to secure by Letters Patent is:

1. A wiper for a circular light transmitter surface, including a bearing mounted concentrically of said surface, and a wiper member carried by the bearing, there being means normally holding the member out of wiping engagement with the transmitter surface.

2. A wiper device for a circular light

transmitter surface, including a bearing mounted concentrically of said surface, and a rockable wiper carried by the bearing, there being yieldable means normally holding the wiper shifted as to the bearing out of wiping engagement with the transmitter surface.

3. A wiper for a circular reflector surface, including a bearing mounted concentrically of said surface, and a wiper member carried by the bearing for rotation against said surface, there being means normally holding the member out of wiping engagement with the reflector surface.

4. A wiper device for a circular reflector surface, including a bearing mounted concentrically of said surface, and a rockable wiper carried by the bearing for rotation against said surface, there being means embodying a link and a weight acting upon the link for normally holding the wiper shifted as to the bearing out of wiping engagement with the reflector surface.

5. A wiper device for a circular surface to be cleaned, said device embodying a rotary member mounted concentrically of said surface, a wiper member hinged for swinging toward and from said surface, there being loading means carried from the rotary member for relative radial movement, said loading means also being connected to rotate with the wiper member for holding the wiper member against the surface and pulling the wiper member at rest away from the surface, and means for rotating the wiper member and loading means.

6. A wiper device for a circular light transmitting bulb surface to be cleaned, said device embodying a rotary member mounted concentrically of said bulb, a wiper member hinged for swinging toward and from the bulb surface, a weight carried from the rotary member for relative radial movement, said weight also being connected to rotate with the wiper member for swinging the wiper member at rest away from the bulb surface and coacting in rotation to swing the member against the surface, and driving means for the member and weight.

7. A wiper device for a circular light transmitting surface and a circular light reflecting surface, said device embodying a rotary member, said rotary member and surfaces being concentrically disposed, a wiper for each surface hinged from the rotary member for swinging toward and from wiping position as to the respective surfaces, a first of said wipers being sustained by the rotary member remote from the center of gravity of said first wiper, a link connecting the wipers in opposing relation, one of said wipers as it falls away in swinging on its hinge mounting from the surface to be wiped thereby being effective in its falling to act through the link connection for shift-

ing the other wiper away from the surface to be wiped by said other wiper, and driving means for rotating the rotary member and through the action of centrifugal force to swing said first wiper into wiping position and thereby through the link draw the other wiper into wiping position.

8. A wiper device for a bulb, having a shade, said device embodying wiper means

for cleaning the bulb and shade, and a motor connected to operate the wiper means.

9. A wiper device for a bulb, having a shade, said device embodying wiper means for cleaning the bulb and shade, a motor for operating the wiper means, and an automatically controlled switch for the motor.

In witness whereof I affix my signature.

JAMES A. H. BELL.
